George M. Gustin, Wabash, Ind., assignor to The
G. M. Diehl Machine Works, Inc., Wabash,
Ind., a corporation of Indiana

Application December 31, 1952, Serial No. 22,947

Term of patent 14 years

(CL. D93—3)

To all whom it may concern:

Be it known that I, George M. Gustin, a citizen of the United States, residing at Wabash, in the county of Wabash and State of Indiana, have invented a new, original, and ornamental Design for a Gang Ripsaw, of which the following is a specification, reference being had to the accompanying drawing, forming a part thereof.

Fig. 1 is a perspective view showing the front and input ends of a gang ripsaw embodying my new design;

Fig. 2 is a perspective view showing the front and output ends thereof;

Fig. 3 is a perspective view showing the rear and input ends of the machine; and

Fig. 4 is a plan view thereof.

I claim:

The ornamental design for a gang ripsaw, as shown.

GEORGE M. GUSTIN.
